NAILING TABLE FOR BOX LIDDING MACHINES

Harry D. Benson, Fresno, Calif., assignor to General Nailing Machine Corporation, Sanger, Calif., a corporation of California

Original application June 2, 1947, Serial No. 751,741. Divided and this application June 7, 1950, Serial No. 166,710

7 Claims. (Cl. 1-15)

1

This application is a division of application Serial No. 751,741, filed June 2, 1947; now Patent No. 2,536,416, dated January 2, 1951.

The invention relates to the box making art and has particular reference to a box conveying and supporting or nailing table unit for use with a box lidding machine to adequately convey the box into and out of the machine and to locate and support the box during the operation of nailing the lid on the box.

In machines employed to apply lids to boxes, particularly those filled or overfilled with contents, considerable pressure is required to compress the lid down onto the box preparatory to nailing in addition to the pressure which is employed to drive the nails through the lids into the ends of the boxes.

It is customary to feed the boxes progressively through the nailing machine by a conveyor mechanism with a temporary stop of the box during the nailing operation and it is an object of the present invention to provide a novel endless chain conveyor feed means for the boxes in combination with a nailing support or anvil and locator means which will rapidly and accurately feed the boxes to the nailing station, accurately hold the box in nailing position during the nailing operation, and then automatically release the box after the nailing operation is complete and deliver it out of the machine; a further object being to have the conveyor element yieldable under the pressure exerted by the nailing head against the box to allow the latter to be brought into a position of rest against rigid stop bars or anvils as the nails are being driven through the lid and into the box ends.

Other objects and advantages will be apparent from a reading of the following specification, read in connection with the accompanying drawings in which

Fig. 1 is a front elevation of a complete nailing machine incorporating the improved feeding and nailing table.

Fig. 2 is a view looking in the direction of the arrows on a line 2-2 of Fig. 1 and is a fragmentary view of one side of the nailing table unit.

Fig. 3 is a cross sectional view taken on a line 3-3 of Fig. 2.

Fig. 4 is a cross sectional view taken generally on a line 4-4 of Fig. 2 but showing the conveyor chain depressed into a position substantially flush with the nailing table bar or anvil.

Fig. 5 is a fragmentary sectional view taken on a line 5-5 of Fig. 2.

Referring to the drawings, there is illustrated

- 1 a box lidding and nailing machine which may be of any suitable type known in the box lidding art in which the nailing unit reciprocates into and out of engagement with the box to effect the nailing operation, the particular machine selected for illustration being of that type shown in co-pending application Serial No. 751,741, and described in detail in that application. Briefly, the same includes a main upstanding supporting frame 1 in which are secured upright transversely spaced vertically slotted guide and mounting posts 2 in which is guided a vertically reciprocable driving bar 3 carrying the nailing units 4 which include chucks 5 which are brought into pressure relation with the box lids to press them closely against the box ends during the nailing operation. Such driving bar 3 is reciprocated by connecting rods 6 on cranks 7 connected in driving relation with a motor 8.
- 2 The present invention is concerned only with the means to feed boxes below the nailing units, a nailing table and means to position and support the boxes during the nailing operation, and all of which will now be described in detail.
- 3 A horizontal nailing table bar 9 extends across of each post 2 laterally inwardly of the latter, and is fixed to a horizontal side plate 10 which extends in the same direction, i. e. lengthwise of the direction of movement of boxes through the machine. The side plates 10 are in turn fixed to locator blocks 11, each of which includes a part extending, in locating relation, in the vertical slot 12 of the adjacent post 2. The locator blocks 11 are fitted with back caps 13 which non-movably but adjustably clamp the locator blocks 11 to the respective posts 2. In this manner the horizontal nailing table bars 9 are rigidly but adjustably attached to the corresponding posts 2.
- 4 A downwardly yieldably mounted, chain supporting bar 14 extends alongside each horizontal nailing table bar; the upper edges of the bars 14 and the upper edges of the bars 9 normally being substantially flush. The chain supporting bars 14 are yieldably mounted by means of bolts 15 engaging through vertically elongated slots 16 in the bars 14; there being leaf springs 17 engaging said bars 14 from below and normally but yieldably urging the same upwardly to the limit of their vertical motion, as shown in Fig. 3.
- 5 Each yieldably mounted bar 14 supports the upper run 18 of an endless chain 19 which turns about end sprockets 20 on opposite end portions of the bar 14; said endless chains 19 being sprocket-driven from a cross shaft 21 below the nailing table assembly, and which cross shaft is

constantly actuated from the motor 8 by means including an endless chain and sprocket unit 22.

Adjustable idlers 23, as shown in Fig. 2, maintain proper tension on the chains 19.

With the above arrangement it will be seen that the upper runs 18 of the chains 19 of the lidding table unit normally run above the upper edge of the horizontal nailing bars 9.

When the machine is in operation, for lidding loaded boxes, the loaded boxes 24 are fed, one at a time and by suitable means, onto the lidding table unit; each box 24, as it reaches the machine, resting at opposite ends on the upper runs 18 of the chains 19, and being fed into said machine thereby. When the box reaches a predetermined position below the lid nailing units 4-5, said box abuts against box stops 25 carried by the side plates 10 adjacent the discharge end of the nailing table assembly and normally projecting into the path of box travel. Each stop 25 is mounted on a shaft 26 journaled in bearings 27 secured to one of the side plates 10. See Figs. 2, 3, and 5.

When each box 24 engages the stops 25, the upper runs 18 of the chains 19 slip under said box, and this slipping action continues during the nailing operation.

As each box 24 comes to rest against the box stops 25, the motor 8 is activated in any conventional manner to drive the cranks 7 to cause the connecting rods 6 to effect reciprocation of the driving bar 3 and nailing units 4-5 through one cycle of movement.

A lid 28 has previously been mounted in the nailing units in the manner described in detail in copending application Serial No. 751,741 and travels with said nailing units. As the nailing units 4-5 move downward and reach the box 24, the nailing chucks 5 press against the lid 28, and the latter presses against the top edges of the ends of the box 24. At this time the box 24 is depressed by the pressure of the chucks 5, causing downward yielding of the upper chain runs 18 and the bars 14 from the position of Fig. 3 to the position of Fig. 4 and until the bottom of the box rests firmly on top of the horizontal nailing table bars 9.

With continued downward motion of the top driving bar 3, the nailing rods of the nailing unit drive through the nailing chucks 5 to drive the nails through the lid into the box end in the usual manner.

Rods 29 are mounted on the driving bar 3 in any suitable manner and depend from the same and slidably engage through sleeves 30 connected to actuating linkage 31 on each stop 25. A collar 32 on each rod 29 engages the corresponding sleeve 30 and depresses it as the top driving bar 3 reaches the bottom of its stroke, and at which time the nailing operation is completed.

When the collars 32 engage and shift the sleeves 30 downward, the box stops 25 swing upwardly, against the tension of torque springs 33, to a clearance position to permit of passage of the lidded box from the machine. These springs 33 are also compressible, being initially loaded or compressed when the box strikes the stops 25. Thus, when the stops are swung upward, the springs urge said stops rearward a limited distance but alongside the box and once the lidded box begins to travel, the stops 25 cannot return to stop position, by the torque of springs 33, until said lidded box is out of the machine.

From the foregoing description it will be apparent that the objectives of the invention are

accomplished in an effective manner. The conveying means operates continuously to carry the boxes to position for nailing. At that point a box is temporarily stopped, pushed to fixed stationary nailing position. When the nailing operation is complete, the box is automatically released whereupon it continues its movement on the conveying means which carries it out of the machine.

While this specification sets forth in detail the present and preferred construction of the device, still in practice such deviations from such detail may be resorted to as do not form a departure from the spirit of the invention as defined by the appended claims.

Having thus described the invention, the following is claimed as new and useful, and upon which Letters Patent are desired:

1. In a nailing machine which includes a frame having transversely spaced upstanding posts, and work conveying and supporting table units attached to the posts; each table unit comprising a horizontal nailing table bar, means securing the nailing table bar intermediate its ends to the post, a chain supporting bar extending horizontally alongside the nailing table bar, means mounting the chain supporting bar on the nailing table bar for limited downward motion from a normally raised position, spring means yieldably resisting such motion, and a driven, endless work-conveying chain mounted in a vertical plane with the upper run traveling on said chain supporting bar and normally in a horizontal plane above the top of the nailing table bar.
2. In a nailing machine which includes a frame having transversely spaced upstanding posts, and work conveying and supporting table units attached to the posts; each table unit comprising a horizontal nailing table bar, means securing the nailing table bar intermediate its ends to the post, a chain supporting bar extending horizontally alongside the nailing table bar, means mounting the chain supporting bar on the nailing table bar for limited downward motion from a normally raised position, spring means yieldably resisting such motion, and a driven, endless work-conveying chain mounted in a vertical plane with the upper run traveling on said chain supporting bar and normally in a horizontal plane above the top of the nailing table bar; the chain supporting bar mounting means including spaced elements projecting outward from the nailing table bar, and the chain supporting bar having vertically elongated slots in which said elements are disposed.

3. In a nailing machine which includes a frame having transversely spaced upstanding posts, and work conveying and supporting table units attached to the posts; each table unit comprising a horizontal nailing table bar, means securing the nailing table bar intermediate its ends to the post, a chain supporting bar extending horizontally alongside the nailing table bar, means mounting the chain supporting bar on the nailing table bar for limited downward motion from a normally raised position, spring means yieldably resisting such motion, and a driven, endless work-conveying chain mounted in a vertical plane with the upper run traveling on said chain supporting bar and normally in a horizontal plane above the top of the nailing table bar; the chain supporting bar mounting means including spaced elements projecting outward from the nailing table bar, and the chain supporting bar having vertically elongated slots in which

said elements are disposed, and said spring means being leaf springs on the nailing table bar bearing against the bottom of the chain supporting bar.

4. In a nailing machine which includes a frame having transversely spaced upstanding posts, and work conveying and supporting table units attached to the posts; each table unit comprising a horizontal nailing table bar, means securing the nailing table bar intermediate its ends to the post, a chain supporting bar extending horizontally alongside the nailing table bar, means mounting the chain supporting bar on the nailing table bar for limited downward motion from a normally raised position, spring means yieldably resisting such motion, and a driven, endless work-conveying chain mounted in a vertical plane with the upper run traveling on said chain supporting bar and normally in a horizontal plane above the top of the nailing table bar; each post having a longitudinal slot therethrough, and said securing means for the nailing table bar including a locator block on said bar engaged in the post slot, and a back cap secured to the locator block in clamping engagement with the post on the side opposite said nailing table bar.

5. In a nailing machine which includes a frame having transversely upstanding posts, and work conveying and supporting table units attached to the posts; each table unit comprising a horizontal nailing table bar, supporting means securing the nailing table bar intermediate its ends to the post, a chain supporting bar extending horizontally alongside the nailing table bar, means mounting the chain supporting bar on the nailing table bar for limited downward motion from a normally raised position, spring means yieldably resisting such motion, and a driven, endless work-conveying chain mounted in a vertical plane with the upper run traveling on said chain supporting bar and normally in a horizontal plane above the top of the nailing table bar; the chain supporting bar terminating at its ends short of corresponding ends of the supporting means for the nailing table bar, and chain en-

gaging sprockets on said supporting means beyond opposite ends of the chain supporting bar.

6. In a nailing machine having an upstanding main frame, upstanding transversely spaced mounting members on the main frame and vertically reciprocable nailing units guided on said members and including chucks movable downwardly for work engagement prior to a nail driving operation, and transversely spaced work supporting table units on the mounting members below the nailing units; each table unit including a horizontal nailing-table bar extending horizontally through the machine, means securing the bar on the corresponding mounting member, a normally raised chain supporting bar extending horizontally alongside and lengthwise of the nailing-table bar, means mounting the chain supporting bar on the nailing-table bar for downward yielding movement from said normal raised position, an endless driven work conveying chain arranged with its upper run riding on said chain supporting bar and normally above the level of the upper surface of the nailing-table bar, and means to simultaneously drive both chains in the same direction, the upper runs of the chains and the corresponding supporting bars yielding under the influence of the downward movement and pressure of the nailing chucks on the work until the latter rests on the nailing-table bars.

7. A structure as in claim 6, with releasable stops on the table units arranged to stop the horizontal travel of the chain-supported work through the machine when said work is in nailing position thereon.
